UNITED STATES PATENT OFFICE.

MARTIN KATZ, OF BROOKLYN, NEW YORK, ASSIGNOR TO FELLS, LENT, CANTOR, KATZ CORPORATION, OF LONG ISLAND CITY, NEW YORK, A CORPORATION OF NEW YORK.

MOUNTING FOR STORE WINDOWS.

Application filed November 8, 1927. Serial No. 231,891.

The present invention relates to mountings for store windows in which the glass thereof is detachably secured along its marginal edges and side faces by sash members 5 or mouldings adapted to be connected to fixed window frames.

Heretofore, a considerable part of the work necessary in cutting, fitting and connecting the several parts together, has been 10 done on the ground, or place where the mounting is required, thus entailing considerable expense both in time and labor.

The objects of the present invention include a form of construction whereby the 15 essential parts of the mounting may be quickly cut to sizes and detachably fitted together at the factory.

The objects also include a construction in which oppositely arranged sash members are 20 provided with clamping faces adjustably disposed to secure glass of variable thickness.

Also, to provide sash members having 25 parts of uniform cross section, including clamping means therefor adapted to be engaged at different points along the length thereof.

Also, to provide sash members arranged 30 with perforations adapted to jointly receive connection screws and serve as air and drainage passages for said members.

For further comprehension of the invention, and of the objects and advantages thereof, reference is had to the following description and accompanying drawing, and to the appended claims in which the various features of the invention are more particularly pointed out.

In the drawing, Figure 1 is an exterior 40 view shown in side elevation of a window pane, and sash mounting embodying the present invention.

Figure 2 is a transverse sectional elevation of a pair of windows disposed one above 45 the other, together with the supporting frames therefor.

Figure 3 is an enlarged fragmental view, partly in section, of the preferred means for clamping the sash members together.

50 Figure 4 is a similar fragmental view showing a modified form of clamping means.

Figure 5 is a longitudinal view of one of the sash members taken along the line 5—5 of Fig. 3.

Referring to Fig. 2 of the drawing, numerals 10 indicate transverse sections of the window frame, and fixed to the latter are the sash members 11 provided with base parts 12 that engage the opposite inner faces of the frame, the opposite side faces thereof being 55 engaged by the mouldings and flanges projecting outwardly from the bases 12 and which serve to fixedly position the sash members 11 to the frame. Projecting from the interior walls 11a of the sash members 60 11 and extending the length thereof, are web sections 13 having bearing faces which engage the marginal edges of the glass 14 and vertically position the latter, the marginal side edges of the glass on the interior 65 70 surface thereof being engaged by the bearing faces 13a projecting from the web sections 13.

The sash members 11 engage the four marginal edges of the glass, the ends of the 75 members being mitred as indicated by the diagonal lines 15, shown in Fig. 1.

For clamping the glass in position, movable sash members 16 are provided having bearing faces 17 that engage the marginal 80 side edges of the glass on the exterior surface thereof, the movable members being supported by the base 12 of the fixed sash members 11. The members 16 are also provided with inwardly extending web sections 85 18 disposed adjacent the web sections 13 of the fixed sash member, the latter sections overlapping the former and serving to prevent displacement of the movable members from the base of the fixed members. 90

As shown in Figs. 1, 2 and 3, the movable sash members 16 also are provided with projecting flanges 19 and 20, the free ends thereof resting upon the base 12 of the fixed sash members 11. These flanges extend 95 the length of the sash members and are each provided with perforations or slots 21 adapted to receive the screws 22, the driving heads thereof engaging the walls of the inner flanges 20 to advance the movable 100 members and effect the clamping action thereof, while the outer flanges 19 permit a free passage for the screws and cover the heads thereof, thus providing clamping connections invisible from the exterior side of 105 the windows. In the preferred form of screw connections, as shown in Fig. 3, the threaded portions thereof engage tooth-

shaped ledges 23 formed on the bases 12 and on the ribs 24 inwardly extending from the wall 11^a of the fixed sash members 11, the ledges extending the length of the sash members in the manner indicated in the fragmental view of Fig. 5, and spaced apart from each other to engage the screw threads on opposite sides.

In the formation of the sash members, the several mouldings, flanges, webs and ledges thereof comprise parts having a uniform cross section throughout their lengths, and in construction, the metal used is heated to a plastic condition and forced under compression through suitably shaped dies resulting in a finished product commonly known as extruded metal.

In this form the sash members may be cut to the required lengths, and the screw perforations or slots punched in the movable member 16 at the desired points along the length thereof, the screw threads obviously being adapted to engage the ledges of the fixed sash members at any and all such points. As thus constructed the work of cutting and detachably fitting the several parts together may readily be done at the factory, and then permanently reassembled in the frames at the point of destination, where the glass may be inserted in the fixed sash members and retained therein by the movable sash members and clamp screws 22.

To provide for the circulation of air between the interior and exterior surfaces of the windows, air passages or perforations 25 are formed in spaced relation through the web sections 13 of the fixed sash members 11 and which communicate with the perforations and slots formed in the flanges 19 and 20 of the movable sash member 16, these passages and screw perforations also serving

as drainage passage for the wash water used for cleaning the windows.

For the accommodation of certain situations, a modified form of screw connection 45 is shown in Fig. 4, in which the screw-engaging ledges 23^a are formed in the movable clamping sash member 16^a, with the body of the screw passing through the wall 11^a of the fixed sash member 11, and the driving 50 head of the screw engaging the outer surface of the wall.

I claim:

1. In a glass-mounting, a fixed frame, a sash member having a base engaging the inner face of said frame, and side members projecting outwardly from said base and engaging the side faces of said frame, said base having a ledge extending lengthwise thereof and transversely shaped to engage the thread of a screw.
2. In a glass-mounting, a sash member having a series of parts arranged to detachably support the glass, the said parts being integral and of uniform cross section throughout the length of said member, said parts including a ledge extending lengthwise thereof and transversely shaped to operatively engage the thread of a screw.
3. A sash member having a ledge extending along the length thereof, the said ledge being transversely shaped to operatively engage the thread of a screw.

4. A sash member having a plurality of ledges extending lengthwise thereof, the said ledges being transversely shaped to operatively engage the thread of a screw.

Signed at New York, in the county of New York and State of New York, this 26th day of October, A. D. 1927.

MARTIN KATZ.
